H. H. LANNING.

WELDING BURNER.

APPLICATION FILED OCT. 6, 1911.

1,038,765.

Patented Sept. 17, 1912.

UNITED STATES PATENT OFFICE.

HOWARD H. LANNING, OF TOPEKA, KANSAS, ASSIGNOR OF ONE-HALF TO HENRY W. JACOBS, OF TOPEKA, KANSAS.

WELDING-BURNER.

1,038,765.

Specification of Letters Patent. Patented Sept. 17, 1912.

Application filed October 6, 1911. Serial No. 653,180.

To all whom it may concern:

Be it known that I, HOWARD H. LANNING, a citizen of the United States, and resident of Topeka, in the county of Shawnee and State of Kansas, have invented certain new and useful Improvements in Welding-Burners, of which the following is a description, reference being had to the accompanying drawing, which forms a part of my specification.

My invention relates to a welding burner wherein pure oxygen and some other suitable gas such as acetylene, hydrogen, natural or illuminating gas, is intended to be used to produce a blow pipe flame suitable for welding purposes.

The object of my invention is to produce a burner which will be light and durable and which can be manufactured and maintained at the least possible cost.

A further object of my invention is to produce a composite burner, the component parts whereof will be readily accessible and at the same time easily removable for repairs or displacement without disturbing the relation of other parts, and without necessitating the entire dismantlement of the burner.

Another object of the invention is the production of a burner whose construction will permit the use of acetylene or other combustible gases under the low pressure at which such gases are usually supplied and at which it is safest, most convenient and economical to generate them, as will be more fully understood from the following detailed description.

In the drawing:—Figure 1 is a partial longitudinal sectional view and partial side elevation of my improved burner. Fig. 2 is a longitudinal sectional view of the burner head and mixing chamber end of the device. Fig. 3 is a cross sectional view taken on the line 3—3 of Fig. 2 looking in the direction of the arrows. Fig. 4 is a detailed view in perspective, to more clearly illustrate the construction of the inner or oxygen nozzle. Fig. 5 is a detailed view in perspective to more clearly illustrate the construction of the main or outer nozzle.

In the exemplification of my invention disclosed in the drawing, 6 and 7 are suitable stop cocks which are intended to be connected to suitable conduits leading to different sources of proper gas supplies; that is, the cock 6 is connected with a supply of

oxygen, while cock 7 is connected with a supply of acetylene or other suitable gas. The stop cocks 6 and 7 are preferably secured to or screwed into a breech block 8 which is provided with ducts or passages 9 and 10. The breech block 8 is removably held in place against one end of the handle portion 11 by the knurled sleeve 12, which screws onto handle portion 11. The handle 11 is provided with a chamber 13, which is adapted to receive suitable filtering material such as mineral wool, felt, asbestos, or the like; and one end of the chamber being preferably provided with wire netting of suitable mesh as at 14, whereby the filtering pack is held away from the outlet end of the chamber. The handle 11 is also provided with a separate passage or duct 15 which communicates with the passage 9 in the breech block, while the passage 10 in the breech block communicates with chamber 13. The opposite end of handle 11 is provided with a pipe 16 which is secured in an outlet opening or port of chamber 13, and also with a pipe or tube 17, which connects with the passage or duct 15 in the handle. The other end of pipe 16 is connected to a T-head 18 and communicates with a chamber 19, see Fig. 2.

The upper part of the T-head 18 is internally threaded to receive the externally threaded sleeve 20. The upper end of sleeve 20 is reduced and internally threaded as at 21, where it receives the upper, externally threaded end of the inner nozzle 22. In order that sleeve 20 may be held in its adjusted position in the upper end of the T-head 18, I provide a lock nut 23 which engages the external threads on sleeve 20 and screws down onto a suitable gasket or washer 24 whereby a tight joint between sleeve 20 and the T-head 18 is provided, which will prevent the leakage of gas around the threads. A gasket or washer 29 is preferably inserted between the reduced portion of sleeve 20 and an annular flange 30 on the inner nozzle 22, so as to insure a tight joint being made between nozzle 22 and sleeve 20.

The upper end of sleeve 20 has secured to it a tubular tip 25, one end of which is provided with a flange 26 which bears against a gasket 27. The tip 25 is held in place by a cap nut 28 which screws onto sleeve 20. The tubular tip 25 receives the end of tube or pipe 17, which is securely

fastened therein, either by being soldered or secured in any other suitable manner.

The lower end of the inner nozzle 22 is provided with an annular flange 31 whereby the nozzle is maintained in a central position within T-head 18. This annular flange 31 is provided with a series of ports or slots 32, arranged about its periphery, so as to permit of communication between the upper and lower portions of chamber 19 in the T-head 18. The lower end of T-head 18 is slightly contracted and internally threaded so as to receive the threaded shank or end 33 of an outer or main nozzle 34; a portion 15 of the nozzle 34 being preferably made hexagonal in shape to permit of the use of a wrench whereby the screwing of the main nozzle into the T-head 18 is facilitated. The shank or upper end of the main nozzle 34 is 20 made to extend beyond its threaded portion so as to abut against the flange portion 31 of inner nozzle 22, and adjacent to its tip 35 without interfering with the slots or ports 32. The shank 33 is provided with ports 25 or perforations 36 arranged in circumferential manner at a point below the upper end, so that when nozzle 34 is in place, the ports will be slightly removed from tip 35, as clearly shown in Fig. 2. The main nozzle 34 is provided with a tapering bore or conical chamber 37, provided with an elongated orifice or mouth 38.

In the employment of my improved burner, the oxygen is allowed to pass 35 through cock 6, when the latter is open, and flow through the passage 9 in breech block 8, into the passage or duct 15 in handle 11, and thence through tube 17 and its connections into the inner nozzle 22 and out through its 40 tip 35 into bore or mixing chamber 37 in main nozzle 34, above perforations or ports 36. The acetylene, or other suitable gas, is admitted through cock 7, by which its flow may be controlled, into the chamber 13 of 45 handle 11. As previously stated, chamber 13 is provided with a suitable filter pack of mineral wool, felt, asbestos, or the like, so as to prevent impurities or solids being carried beyond chamber 13. The filtered 50 acetylene, or other gas, passes out of chamber 13 into pipe 16 and into the chamber 19 in T head 18; from chamber 19, the acetylene passes through the ports or slots 32 into the lower part of chamber 19 from 55 whence it passes through ports 36 and into the mixing chamber 37 beneath the point where the oxygen enters said chamber. Here the acetylene diffuses with the oxygen, so that a mixture of oxygen and acetylene 60 will be discharged through the orifice or mouth 38 of main nozzle 34, at which point combustion takes place.

By reason of the manner of securing the inner nozzle 22 within the T-head 18, 65 namely, through the medium of sleeve 20,

it is apparent that a gas tight joint can be formed between the inner or oxygen nozzle 22 and the main nozzle 34, regardless of any irregularities in the lengths of either nozzle, as the lower end of the inner nozzle 22 can 70 be made to come up flush against the extended end or shank of main nozzle 34 by screwing sleeve 20 into the T-head the necessary distance. The sleeve 20, together with the inner nozzle 22, will be held in its 75 adjusted position by the lock nut 23.

The bore or mixing chamber 37 of main nozzle 34 is preferably made conical as previously stated, although it may be made any suitable shape to adapt it to different requirements; it is important, however, that the walls of the mixing chamber 37 be absolutely smooth, and that the orifice or mouth 38 thereof be perfectly round, as clearly shown in Fig. 2, otherwise, the flame is very 80 apt to flash or strike back through the orifice or mouth 38 and set fire to the mixed gases within chamber 37. This would soon result in the absolute destruction of the nozzle. As the main nozzle is not only subjected to intense heat but is also subjected to more or less abuse whereby its mouth or orifice is apt to be distorted, it would be necessary under ordinary conditions to discard the nozzle; but in order to extend the 85 life of the nozzle, I have made the mouth or orifice cylindrical for a short distance back, so that any distortion at the mouth may be corrected by filing off a sufficient portion, 90 without, however, altering or interfering with the shape and size of the mixing chamber 37. Should the main nozzle become defective, it is evident that a new one can readily be inserted in the T-head without necessitating the renewal of any of the other 95 parts of the burner. By providing the main nozzle 34 with its extended end or shank 33, which encircles the tip of inner nozzle 22, it is evident that a mixing chamber is produced by the close contact between 100 the two members. This permits of the employment of an inner nozzle having a tip or discharge orifice of the desired size without requiring a different outer or main nozzle, so that either one of the nozzles may be 105 replaced without the necessity of changing the other.

The dimensions of mixing chamber 37, the size of the orifice in tip 35 and its position relative to the ports 36, all depend upon the gas pressures used as well as upon the diameter of the orifice or passage 38 at the mouth of the main nozzle; and the proper diameter of passage 38 is determined by the class of welding that is desired to be done; for instance, the welding of heavy pieces of metal requires a relatively larger passage 110 than that required for lighter work. With my improved construction, therefore, it is 115 apparent that a number of nozzles 34 pro- 120 125 130

vided with passages 38 of different sizes may be interchanged, thus adapting my improved burner to different requirements, and obviating the necessity of an entirely different burner. The same is true in connection with the inner or oxygen nozzle 22, as it is evident from the construction shown and described that inner nozzles of various lengths beyond flange 31 may be employed, 10 provided with tips 35 having orifices of different sizes. By choosing, therefore, the proper combinations of inner or oxygen nozzles and outer or main nozzles, the burner can be quickly adjusted for any class 15 of welding, as well as other varying gas pressures within reasonable limits.

As previously described, the filter pack inclosed in chamber 13 is preferably made of some non-combustible substance, but of 20 a nature that will permit of the passage of gas. The filter pack serves the double purpose of filtering the gas so as to prevent particles of solid matter being carried by the gas to the burner-tip where it would clog up 25 the small orifices or affect the chemical or physical properties of the flame, and also prevents the propagation of any flame or explosion of the source of gas supply.

By having the different gas controlling 30 means or cocks secured to the breech block or member 8, it is evident that the breech block can be readily removed for the purpose of cleaning or renewing the filter pack within handle 11. The construction of handle 35 11 and breech block 8, together with the manner of securing the two together, permits of ready access to chamber 13 without the necessity of disconnecting any pipes or tubes, it merely being necessary to close 40 cocks 6 and 7 and thereby shut off the flow of the gases. Another advantage resulting from the construction shown and the manner of connecting the handle and breech block, is that another form of breech block, 45 for instance one having a third cock for an auxiliary jet of oxygen to be used for cutting purposes, can be easily and quickly applied in place of the one used for the usual or ordinary run of work in connection with 50 which burners of this class are used.

I have shown and described what I believe to be the simplest and best construction of my invention, but the same may be altered in certain details as practice may dictate without, however, departing from the spirit of my invention, and I do not wish to be understood, therefore, as limiting myself to the exact construction shown and described, but

What I claim and wish to secure by Letters Patent, is:—

1. A burner of the class described, comprising a hollow member, a second member arranged within the hollow member, the second member being provided with an annular flange in proximity to the one end

thereof adapted to engage the wall of the hollow member and maintain the second member substantially at the longitudinal center of the hollow member so as to provide a chamber intermediate of the walls 70 of both members, said annular flange being provided with a series of openings whereby communication between portions of the chamber on opposite sides of the flange is established, means secured to the other or 75 upper end of the second member, arranged to screw into the hollow member, whereby the second member is adjustably secured to the hollow member, means whereby the first mentioned means is locked in the adjusted 80 position and a gas tight connection maintained, said second member being provided with a tip at the lower end thereof, and an outer or main nozzle provided with a tapering passage extending longitudinally there- 85 through and having a reduced extended end or shank adapted to abut against the end of the second member and incase the tip thereof, the extended end or shank being provided with one or more ports at a slight 90 distance from the end thereof whereby communication between the chamber in the hollow member and the tapering passage in the main nozzle is established and said passage utilized as a mixing chamber, the outer 95 or main nozzle being removably secured in the end of the hollow member.

2. A burner of the class described, comprising a hollow outer member, a second member arranged within the hollow member, the second member being provided with a passage extending longitudinally there- 100 through and having an annular flange in proximity to each end thereof, whereby the position of said second member relative to 105 the walls of the hollow member is maintained and a chamber intermediate of the members provided, the flange adjacent the one end of the second member being provided with a series of openings for the pas- 110 sage of gas therethrough, a sleeve portion arranged to receive the other end of the second member and adapted to screw into the other end of the outer member whereby the second member is ad- 115 justably secured within the outer member, means whereby said sleeve portion is locked in its adjusted position and a gas tight connection maintained, and an outer or main nozzle provided with a reduced extended 120 end or shank arranged to screw into the outer member and adapted to abut against the end of the second member, said shank being provided with one or more ports whereby communication between the chamber 125 in the outer member and the nozzle interior is established.

3. In a burner of the class described, an outer member provided with an opening in its side for the admission of a gas, a nozzle 130

removably secured at one end of said member and having a reduced end extending into said member and provided with a passage extending longitudinally therethrough, diminishing in size toward the outer end of said nozzle, said reduced end being provided with ports arranged at predetermined points, a second nozzle extending longitudinally within said member and provided with a tip adapted to abut against the extended end of the first mentioned nozzle whereby the gases flowing through said second nozzle and through the outer member will be made to mingle in the passage of the first mentioned nozzle, the upper end of said second nozzle being connected with a source of gas supply, and means whereby said sec-

ond nozzle is adjustably secured within said member.

4. In a burner of the class described, an integral handle portion provided with a number of passages extending longitudinally therethrough, one of said passages being provided with a filter pack, a breach block provided with a number of passages extending therethrough, adapted to communicate with the passages in said handle portion and with said breach block whereby the latter is removably secured to said handle portion. 20 25

HOWARD H. LANNING.
